RECORD SHEET SUPPORTING DEVICE

Harold Hansen, Fresno, Calif.

Application March 31, 1947, Serial No. 738,474

6 Claims. (Cl. 281—44)

1

This invention relates to, and it is an object to provide, a manually portable device, of multi-sided configuration, adapted to support a plurality of record sheets on said sides for selective use.

While especially designed for use in connection with lumber tally sheets, the device obviously may be used for other types of recording where a plurality of sheets are required.

In tallying lumber at mills or the like, the person keeping the record or tally has heretofore used a number of tally boards to which the record sheets are attached; each sheet corresponding to a different size of lumber. Thus, each time the size of the lumber changed, it was necessary to put down one tally board and to pick up another. This was inconvenient and resulted in considerable loss of time.

It is therefore another object of this invention to provide a hand-supported device which is multi-sided, with each side adapted to support a corresponding tally sheet, there being a handle by means of which the device is held for use, and also readily changed to position any selected side and corresponding tally sheet uppermost.

An additional object of the invention is to provide a device, as in the preceding paragraph, which comprises a rectangular box frame having side boards thereon to support the tally sheets; one end of the frame having an opening for entry of the tally keeper's arm, and there being a handle in the frame for hand engagement whereby to manually carry the device and change the position of the tally sheets as desired.

A further object of the invention is to provide a simple and inexpensive device, and yet one which will be exceedingly effective for the purpose for which it is designed.

These objects are accomplished by means of such structure and relative arrangement of parts as will fully appear by a perusal of the following specification and claims.

In the drawings:

Fig. 1 is a perspective view of the device as in use.

Fig. 2 is a sectional plan of the device.

Referring now more particularly to the characters of reference on the drawings, the record sheet supporting device comprises a rectangular box frame 1 fitted, on the four sides thereof, with flat side boards 2.

The side boards are of greater length than the frame 1 whereby they project beyond opposite ends of the frame, as exposed end flanges 3, for the purpose hereinafter described.

2

The frame 1 includes end boards 4 and 5; the latter being formed with a relatively large-diameter circular access opening 6, whereby the record keeper's arm may be projected into the device through such opening, in the manner shown in Fig. 1.

At the end opposite the opening 6 the end board 5 is fitted, within the box frame 1, with a central, axially inwardly projecting handle 7 fixed to the end board 4 by a screw 8.

A separate record or tally sheet, indicated at 9, is disposed in engagement with each of the flat side boards 2 on the outside of the same.

The record or tally sheets 9 are releasably secured to corresponding side boards 2 by means of spring clamps 10 which engage over the exposed end flanges 3 of said side boards and frictionally clamp the adjacent portions of the sheets 9 thereto.

When the above described device is in use, as example for tallying lumber, the tally keeper places one arm through the access opening 6 and grasps the handle 7.

The device is thus effectively supported for use of the record or tally sheets 9, each of which represents the record for a different size of lumber. As the size of the lumber changes, all the tally keeper need do is rotate the device by the handle 7 until the proper sheet 9 is uppermost for use.

In this manner a plurality of record sheets are in hand for ready and selective use, without the necessity of handling separate boards and sheets, as has heretofore been the practice.

While the device is herein shown as four-sided, it is understood that a multi-sided device, with a greater number of sides, can be provided within the contemplation of this invention.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent are desired:

1. A manually portable device for supporting a plurality of record sheets exposed for selective use, the device comprising a multi-sided support, each side being a flat board adapted for engagement on the outside by a separate record sheet,

means to releasably secure the record sheets to said boards, and a handle on the support in position for manual carrying of the device and rotation thereof to position the sheets uppermost selectively; the support being a box having an access opening in one end thereof, and the handle being mounted within the box.

2. A manually portable device for supporting a plurality of record sheets exposed for selective use, the device comprising a multi-sided support, each side being a flat board adapted for engagement on the outside by a separate record sheet, means to releasably secure the record sheets to said boards, and a handle on the support in position for manual carrying of the device and rotation thereof to position the sheets uppermost selectively; the support being a box having an access opening in one end thereof, and the handle being elongated and mounted in the box on the opposite end thereof in axially projecting relation inwardly and parallel to the side boards.

3. A manually portable device for supporting a plurality of record sheets exposed for selective use, the device comprising a multi-sided box frame, flat side boards secured to the frame, each side board being adapted for engagement on the outside by a separate record sheet, means to releasably secure the record sheets to corresponding side boards, end boards secured to the frame, one end board having an access opening therein, and a handle in the box frame secured to the opposite end board.

4. A manually portable device for supporting a plurality of record sheets exposed for selective use, the device comprising a multi-sided box frame, flat side boards secured to the frame, each side board being adapted for engagement on the outside by a separate record sheet, means to releasably secure the record sheets to corresponding side boards, end boards secured to the frame, one end board having an access opening therein, and a handle in the box frame secured to the opposite end board; said handle

being straight and secured to said opposite end board centrally thereof and projecting axially toward but terminating short of said access opening.

5. A manually portable device for supporting a plurality of record sheets exposed for selective use, the device comprising a multi-sided box frame, flat side boards secured to the frame, each side board being adapted for engagement on the outside by a separate record sheet, means to releasably secure the record sheets to corresponding side boards, end boards secured to the frame, one end board having an access opening therein, and a handle in the box frame secured to the opposite end board; the side boards projecting at opposite ends beyond the end boards as exposed end flanges, and said securing means being spring clamps engaged over said flanges.
- 10 15 20 25 30 35
6. A manually portable device for supporting a plurality of record sheets exposed for selective use, the device comprising a multi-sided box frame, flat side boards secured to the frame, each side board being adapted for engagement on the outside by a separate record sheet, means to releasably secure the record sheets to corresponding side boards, end boards secured to the frame, one end board having an access opening therein, and a handle in the box frame secured to the opposite end board; said access opening being circular, and the handle being straight and projecting axially toward but terminating short of said circular access opening.
